UNITED STATES PATENT OFFICE.

JOSEPH RABER, OF DETROIT, MICHIGAN, ASSIGNOR TO BURROUGHS ADDING MACHINE COMPANY, OF DETROIT, MICHIGAN, A CORPORATION OF MICHIGAN.

ADDING-MACHINE.

1,270,868.

Specification of Letters Patent.

Patented July 2, 1918.

Application filed May 20, 1912. Serial No. 698,568.

To all whom it may concern:

Be it known that I, JOSEPH RABER, a citizen of the United States, residing at Detroit, in the county of Wayne and State of Michigan, have invented certain new and useful Improvements in Adding-Machines, of which the following is a specification.

My invention relates to power-driven machines and is hereinafter described in connection with adding machines driven by an electric motor, though it may obviously be employed with other forms of motors. The purpose of the invention is to automatically shut off the power when the adding machine is not being used. Thus, if the motor of a machine provided with my improvement is set in operation and the machine not used, or when the use of the machine is discontinued after it has performed its work, the motor is automatically brought to rest after a definite time has elapsed since the last manipulation of the machine. In the specific form of the device herein shown and described in which the driving device is an electric motor, the switch controlling the supply of current thereto is automatically shifted by my device to open the circuit of the motor. If, however, any other form of motor be employed for driving the adding machine, the same timing mechanism may be employed to shut off the supply of motive fluid. Or, if the power is derived from a source which drives other mechanisms my device may be employed to shift a clutch to disconnect from the source of power in a manner which will be obvious to any mechanic.

The invention by which the above result is accomplished consists in certain novel features of construction and combination of parts, the essential elements whereof are recited in the appended claims, and a preferred form of embodiment of which is described in detail hereinafter and fully illustrated in the accompanying drawings forming a part of this specification. Of said drawings, Figure 1 represents in side elevation so much of an adding machine as is necessary to an understanding of my invention with a driving electric motor attached thereto, to which my device is applied; Fig. 2 is a side elevation on an enlarged scale similar to Fig. 1, but showing a portion only of the same features of con-

struction, parts being removed or shown in section to better reveal the elements to which my invention relates; Fig. 3 is a view in elevation at right angles to the planes of Figs. 1 and 2, but showing the base or support for the mechanism in section, the parts of the machine shown being those shown in Fig. 2, but on the scale of Fig. 1; Fig. 4 is an elevation similar to Fig. 3, but showing parts in section upon the line 4-4 of Fig. 2; Figs. 5 and 6 are detail views showing certain parts of the mechanism shown in Fig. 2 but in different positions; Fig. 7 is a section upon the line 7-7 of Fig. 2 at right angles to the plane of said figure, certain parts being shown in elevation.

The invention is shown and described in connection with the form of electric drive for adding machine disclosed in the patent to Vincent, No. 866,750, issued September 24th, 1907, to which reference may be made for a detailed disclosure of certain features which are old in themselves, but shown in the accompanying drawings to aid in an understanding of the present invention. It will not, therefore, be necessary to fully describe these features, but in the following detailed description I shall merely identify them and state their relation to the present invention.

Referring more particularly to Fig. 1 of the drawings, the frame of the adding machine proper is shown at 7 as mounted upon a suitable base 8, to the under side of which is secured a casting 9 which supports a driving motor 10, power transmitting and controlling mechanism inclosed in a casing 11 and timing mechanism for automatically opening the circuit of the electric motor, inclosed in a housing 12. The motor may be of any well-known or approved type and is supplied with power current through a conductor 13 connected to a switch box 14 containing a switch of a suitable type and well-known form, being shown in dotted lines in Figs. 1 and 2, as a knife switch. The main supplying current through the switch to the motor is shown at 15, Fig. 1. The knife 16 of the switch is pivoted at 17, (as shown in dotted lines, Fig. 1), normally held in open position by a spring 18, and depressed to close the circuit by a push button or rod 19. The latter slides vertically in a hous-

ing 20, and is provided with annular shoulders 21 and 22, with which a catch 23 engages through an opening 24 in the housing, the catch being pivoted at 25 to lugs upon the switch housing, and having an integral arm 26 which is connected to the automatic timing mechanism in a manner which will appear later. The armature shaft 27 of the motor extends through the casing 11 and carries a worm 28 therein which meshes with the worm wheel 29, loosely mounted upon a shaft 2, which, through an arm 30 thereon, a link 31 and an arm 32 on the rock shaft 100 of the adding machine proper oscillates the latter in the manner set forth in the Vincent patent above referred to. When an oscillation is to be given to the shaft 100, the worm wheel 29 is clutched to shaft 2 by a mechanism which is fully described in said 20 Vincent patent but which need be only briefly referred to here. A ring 4 is fixedly mounted upon the side of the worm wheel 29 and provided on its exterior periphery with a continuous series of semi-cylindrical transverse grooves 4^a (see Fig. 4). A disk 6 is rigidly mounted upon the shaft 2 and provided with a flange 6^a which overhangs the ring 4 and carries at one point an interlocking semi-cylindrical key or clutch member 5, which is journaled for oscillation in the disk, and provided at its outer end with a mutilated or partial gear 5^b. Upon the hub of the disk 6 is revolvably mounted an arm 5^a whose hub is formed with a series of 35 teeth engaging the gear 5^b, the arm being urged by a spring 5^c, shown in said Vincent patent, in a direction to turn the key into engagement with one of the grooves of the ring above referred to. At its outer end the 40 arm projects beyond the periphery of the disk and passes or comes into contact with a semi-cylindrical stop 5^d according to the position occupied by the latter. The stop is mounted upon a journal 5^e which is partially rotated to bring the stop into or out of the path of the arm by means which will be hereafter described. It will be apparent that when the stop is turned out of the path of the end of the arm, the latter, under the 45 influence of a spring and by reason of the engagement of the teeth thereon with the mutilated gear 5^b will revolve the key 5 into one of the notches or grooves upon the ring 4 attached to the constantly rotating worm 50 wheel, and the parts being thus keyed together the shaft 2 will be given a complete rotation which will be terminated by the arm 5^a again coming in contact with the stop 5^d, if the latter has been turned into its path, 55 whereby the key will be given a partial rotation against the tension of its spring to release the ring 4. Each time, therefore, that the stop is turned out of the path of the arm the shaft 100 is given a complete oscillation. All this construction is fully set out

in the Vincent patent above referred to which may be consulted for a fuller explanation thereof.

Before proceeding to a detailed description of the specific embodiment of my invention disclosed in the accompanying drawings, I will give a brief outline of the general nature of operation thereof as applied to the above described machine. The switch is, as above stated, provided with a catch 70 which maintains it in closed position after it has been depressed to start the motor. A trip is provided, however, to release the catch a definite period after each manipulation of the machine. If, however, a second 75 manipulation or a series of manipulation takes place within the period the latter is correspondingly extended so that as long as the manipulations occur with the required frequency the switch remains closed. For 80 this purpose the trip for operating the catch is, during the operation of the machine, normally maintained in retracted or inoperative position by a dog which is partially under the control of the clutch actuating means or 85 any other manipulative part of the machine and otherwise controlled by a disk which is continuously turned by the motor when the latter is in operation. The timing disk periodically throws the dog out of engagement 90 with the tripping device or hammer and into engagement with a detent. The release of the trip from the dog, however, does not immediately effect the operation of the catch but it is prevented from operating by being 95 held for a definite period from its release from the dog by the timing disk itself which only permits the operation of the trip at a definite point in its revolution. The detent referred to above is, however, actuated to 100 release the dog every time the manipulative part of the machine is actuated and when so released the dog is again in position to engage the trip and prevent its operation during the time when the timing disk is in position to permit the same. Thus so long as the manipulative part is actuated within the predetermined period the trip is prevented 105 from moving the catch to release the switch, but if the said period is exceeded without 110 a manipulation of the machine the trip engages the catch and stops the machine.

Beyond the worm 28 the armature shaft is spliced at 33, extended through the wall of the casing 11 and provided with a second 115 worm 34 (see Fig. 3) which meshes with a worm wheel 35 mounted upon a counter shaft 36. The latter also carries a worm 37 which engages a worm wheel 38 upon the timing shaft 39 in housing 12 (see Figs. 1, 2 and 7). 120 By reason of this train of reducing gear the time shaft turns at a very low speed when compared with the speed of the shaft 2, by which the rock shaft of the adding machine is operated. Upon the timing shaft is fixed 125 130

a disk 40 which is generally circular in outline, but indented or notched at 41 and provided with a cam surface at 42 for a purpose which will appear later. The disk 40 governs the stroke of a hammer 43 which is pivoted within housing 12 at 44 and is formed with the nose 45, which normally rides upon the periphery of the disk 40. A coil spring 46 attached at one end to a stationary stud 47 upon the housing 12 engages at its other end in an opening 48 in the hammer body, normally holds the nose 45 into contact with the periphery of the timing disk and swings the hammer when the nose thereof comes 15 opposite the notch in the disk unless the hammer is restrained by other means to be presently described. The hammer member 43 is also formed with an offset arm 49, which overlaps the face of the disk and carries near 20 its outer end a striking dog or pawl 50 pivoted at 51 and normally held in the position shown in Fig. 2, with an edge against the stops 51^a by means of a coil spring 52. The pawl 50 is further provided with an additional wing or arm 53, which, when the hammer approaches the end of its stroke, comes in contact with a stationary stud 54 on a wall of the casing for a purpose which will appear. Within the casing is also 25 mounted a lever 55, one end 55^a of which projects into the path of the dog 50, to be struck thereby when the hammer swings forward, and to the other arm 55^b is attached the link 55^c connected to the arm 26 30 of the catch 23, above referred to for operating it. A spring 56 normally holds the arm 55^a of the lever against the stop 57 and in position to be engaged by the dog or pawl 50, the connections and proportions of the 35 lever, link and catch being such that the last named element projects over the shoulder 21 or 22 upon the push rod 19, when the arm 55^a of the lever is in contact with the stop 57. A dog 58 is pivoted in the housing 40 at 59, and is notched at its outer end as at 45 60 to engage a squared stud 61 upon the side face of the hammer 43 to hold the latter away from the disk and prevent its operating the lever and catch to release the 50 switch. The dog is further provided with an upstanding spur 62, which is adapted to be engaged by a latch 63 to normally hold the notch 60 from engagement with the squared stud 61, a spring 64 connected to the 55 rear end of the dog at 65 and to the latch at 66 serving to hold these members normally in engagement with each other and to lower the notched end of the dog when released. In order to reengage the dog with the latch 60 after it has been released, the former is formed with a projection 58^a, which, when the dog is down, is engaged by a roller 58^b on the disk and raised to permit the latch 63 to spring over the spur 62.

65 In Figs. 1 and 2, I have shown the means

employed in the machine of the Vincent patent above referred to for actuating the detent 5^c for the clutch between the shaft 2 and the worm wheel mounted thereon and by which it is driven, and it will be sufficient for the present purpose to refer very briefly to this mechanism. A finger bar 36^a is mounted to reciprocate vertically near one edge of the frame of the adding machine at the right of the bank of keys, the latter being omitted from the present showing for the sake of clearness, and a pair of levers 36^c and 36^d support the finger bar through the posts 36^b, 36^b, to which the levers are pivoted at their outer ends. The inner ends of the 70 levers are connected at 36^c by a pin and slot connection, and are normally held with their outer ends elevated by the coil spring 36^e connecting the levers, as shown in Fig. 1. The lever 36^d is extended beyond its connection with lever 36^c and provided with a headed stud e^a working in a slot in the upper end of a vertical bar 36. As shown in Fig. 2 the bar 36 is reduced at its lower end and extends through an eye or opening in 80 the outer end of arm 5^d, which is pivotally mounted upon the screw bolt 5^e upon the side of the housing 12', there being a coiled cushioning spring 36' surrounding the bar between the arm and shoulder 36'. The flat 85 hub of the arm 5^d is of large diameter and provided upon its upper edge with gear teeth 5^f forming in effect a mutilated gear which intermeshes with the teeth 5^g of a disk fixed upon the outer end of the rock 90 shaft 5^b (see Fig. 4), carrying the detent 95 which controls the clutch between the shaft 2 for operating the adding machine and its driving mechanism. The reference numeral 300 designates the usual tubular stub shaft 100 of the adding machine, which may be of the type disclosed in Burroughs Patents Nos. 504,963 and 505,078 of June 12, 1893, and at 311 is shown the full stroke sector, also a 105 common element of such adding machines, and since these elements, as well as the vertical bar 36 and the clutch mechanism and connections are fully described in the Vincent patent, to which reference has been 110 made, no further description of them need 115 be given here. The only modification of this part of the mechanism which is peculiar to my invention consists in the arm 5^m formed integral with the disk 5^x, and which is adapted, when said disk is rotated, to throw 120 the clutch into engagement, to descend upon the stud 68 upon the outer end of an arm 69, formed integral with the latch 63. The operation of my invention may now 125 be understood. When it is desired to use the machine, the push rod 19 is depressed and the switch governing the supply of current to the motor closed thereby, the catch 23 snapping over the shoulder 22 and holding the push rod depressed for the time being, 130

and the motor shaft revolves continuously until the switch is again opened as hereinafter described. The armature shaft through the worm 28 turns the worm wheel 29, and 5 through the reducing gearing 34, 35, 37 and 38 slowly turns the timing shaft. For each adding operation, the operator, after depressing the proper keys, strikes the finger bar 36^a, raising the vertical bar 36 thereby 10 causing the detent 5^c to release arm 29 and throwing in the clutch between the worm wheel and the shaft 2 as heretofore described, thereby effecting an operation of the rock shaft 100. After each operation, 15 the operator immediately releases the finger bar 36^a and thereupon the vertical bar 36 drops, permitting the detent 5^c to release the clutch after one revolution of the shaft 2. The motor, however, will continue its revolution 20 and continue to turn the timing shaft and the timing disk 40, until stopped by the action of the latter.

As will be seen later at the time the current is cut off and the motor and its driven parts come to rest, the timing mechanism is in the position shown in Fig. 5. On depression of the push bar 19 and the consequent closing of the circuit, the revolution of the timing disk forces the nose of the hammer out of the notch in the disk and it rests upon the latter until the notch in the disk again approaches the nose of the hammer. In Fig. 2, the parts are shown in the position which they occupy just after 30 the timing disk has begun to revolve and before any manipulation of the finger bar 36^a. If there has been no operation of the finger bar and consequent release of the dog 58 by the detent 63, the nose of the hammer, 35 on continued rotation of the disk will ride over the cam projection 42 and fall into the notch of the disk, permitting the hammer to be drawn forward by spring 46, whereby the dog 50 strikes the lever 55 and through 40 the link 55^c draws the catch 23 to release the push rod 19. Immediately after the dog 50 strikes the arm 55^a, the other wing or branch of the dog comes in contact with the stationary stud 54 and draws the dog 45 away from the face of the arm 55^a permitting the lever and catch to resume their normal position. When the catch is withdrawn, the switch is opened under the pressure of its spring, and the current being 50 thus shut off and the motor stopped, the timing device comes to rest with the nose of the hammer in the notch of the timing disk. If, however, during the period that the circular part of the periphery of the disk is 55 moving past the nose of the hammer, the finger bar 36^a is operated, it causes the arm 5^m to engage the stud on the arm 69 and withdraw the catch 63 to release the dog 58 which thereupon comes forward with its 60 outer end in contact with the squared lug 65

61. When, with the parts in this condition, the cam projection 42 on the timing disk reaches the nose of the hammer it forces the latter back until the squared lug 61 thereon enters the notch 60 in the dog 58, 70 (see Fig. 6). On the further revolution of the disk and while the notch therein is beneath or adjacent the nose of the hammer the latter is retained in inoperative position by the dog. Shortly after the notch 41 in 75 the disk has been carried past the nose of the dog the roller 58^b wipes past the projection 58^a upon the dog 58 and forces the latter backward until the spur 62 is again engaged by the catch 63, the hammer in 80 the meantime being released and permitted to come forward into contact with the timing disk. If the finger bar is again manipulated before the cam on the disk periphery wipes under the nose of the hammer, the 85 operation of the dog 58 will be repeated and the hammer prevented from tripping the catch to shut off power. On the other hand, if no such manipulation takes place the dog remains under control of the catch 90 63, and when the notch in the disk comes opposite the nose of the hammer the latter gives a stroke to the lever controlling the catch and permits the switch to open the 95 circuit. The machine, as above stated, always comes to rest with the nose of the hammer in the notch of the disk as shown in Fig. 5.

The timing disk may be given any desired speed of revolution by suitably proportioning the reducing gearing by which it is driven from the motor and in practice it is given such a speed that any ordinary manipulation of the machine will prevent the shutting off of current to the motor. If, 100 for example, the shaft be given three-quarters of a revolution or a revolution per minute, the normal operation of the machine will be sufficient to prevent the opening of the switch. Obviously, if for any reason 105 it is desired to stop the motor at any other position of the timing shaft than that shown in Fig. 5 it may be done by tripping the catch 23 by hand. For this purpose the stud or handle 26', shown more particularly 110 in Fig. 3, may conveniently be employed.

It will be understood that the description of the specific form of apparatus embodying my invention is for the purpose of exemplification only, though it is at present my preferred form, and various modifications and changes may be made, not only in the source of motive power and character of the cut-out mechanism, as suggested above, but in the various features of the timing mechanism itself and its connections to the motor 120 without departing from my invention so long as the structures embody the features and principles of the following claims.

It may be added that I do not claim to 125 130

be the first to provide a motor-driven adding machine with means for cutting off the current to the motor a predetermined period after manipulation of the machine has ceased. A construction for accomplishing this purpose is to be found in the patent to Foster No. 974,480, patented November 1, 1910. In the construction there shown, however, the timing of the cut-out does not depend upon a part continuously driven from the motor, but on a pneumatic retarding device which is re-set or re-primed at each revolution of the adding machine operating shaft.

15 I claim:

1. In an adding machine and in combination with the machine proper, a motor, motor controlling means, normally inoperative connections between the motor and the machine proper for driving the latter, manipulative means for rendering the connection operative to effect an operation of the machine, timing mechanism constantly driven by the motor during the operation of the latter, connections controlled by the timing mechanism for controlling the operation of the motor whereby the latter is stopped after a predetermined period has elapsed since an operation of said manipulative

20 means.

2. In an adding machine and in combination with the machine proper thereof, a motor, normally inoperative connections between the motor and said machine for driving the latter, manipulative means for rendering such connection operative, a timing mechanism constantly driven by the motor when in operation, a motor controller, means normally restrained by the timing means for causing an operation of the motor controller and means under the control of said manipulative means for preventing the operation of the controller during a portion of the cycle of movement of the timing mechanism.

3. In a machine of the class described, a motor, a manipulative element of the machine controlling the operation of the machine by the motor, timing means continuously driven by the motor, means for stopping the motor and connections whereby the timing means restrains the stopping means from operation for at least a predetermined period after the operation of the manipulative means has ceased.

4. In a device of the class described, the combination of the machine proper, an electric motor for driving the same, a timing mechanism driven by the motor, a clutch between the motor and machine, a switch for starting and stopping the motor when the clutch is open and connections between the timing mechanism and switch for controlling the latter.

5. In a device of the class described, the

combination of the machine proper, a motor for driving an element thereof, manipulative means for controlling the operation of said element by the motor, timing means continuously and positively driven by the motor, and connections whereby the timing means shuts off power from the motor after a predetermined period has expired since the operation of the manipulative means has ceased.

6. In a device of the class described, the combination of the machine proper, a motor for driving an element thereof, manipulative means intermittently operable, timing means continuously and positively driven by the motor, and connections whereby the timing means causes power to be shut off from the motor after a predetermined period since the operation of the manipulative means has ceased.

7. In a machine of the class described in combination with the machine proper, a motor for driving an element thereof, a clutch between the motor and said element, manipulative means for controlling the clutch, timing means continuously and positively driven by the motor, and connections whereby the timing means causes power to be shut off from the motor after a predetermined period since the operation of the manipulative means has ceased.

8. In a machine of the class described, a motor for driving one of the elements thereof, a clutch intermediate the motor and said element, timing means continuously driven by the motor, connections controlled thereby and controlling the supply of power to the motor, and manipulative means connected to the clutch for throwing the same into and out of engagement and to said connections to prevent their operation to shut off the power.

9. In a machine of the class described, and in combination with the adding machine proper, a motor, timing mechanism continuously driven from the motor, connections under the control of the timing mechanism for stopping the motor and connections to the timing mechanism under control of a manipulative element of the machine proper for preventing the stoppage of the motor.

10. In a machine of the class described, and in combination with the adding machine proper, a motor, a clutch between the machine and motor, timing mechanism continuously driven from the motor, connections under the control of the timing mechanism for stopping the motor and connections to the timing mechanism under control of a manipulative element of the machine proper for preventing the stoppage of the motor.

11. In a machine of the class described, and in combination with the machine proper, a rotary motor for driving the same, a tim-

- ing shaft continuously driven from the motor, connections under the control of the timing shaft for stopping the motor and connections under the control of the manipulative element of the machine for preventing the stoppage of the motor.
12. In a machine of the class described, and in combination with the machine proper, a rotary motor for driving the same, a timing shaft continuously driven through reducing gearing from the motor connections under the control of the timing shaft for stopping the motor and connections under the control of the manipulative element of the machine for preventing the stoppage of the motor.
13. An adding machine including a manipulative means, a motor, means for supplying the motor with actuating fluid, means adapted to connect the supply means with the motor but spring-pressed to normally disconnect the supply of motive fluid from the motor, a catch for holding the connecting means in closed position, a timing mechanism continuously driven from the motor and operating to release the connecting means from the catch and connections under the control of the manipulative element for preventing the release of the connecting means by the timing mechanism.
14. In a machine of the class described and in combination with the adding machine proper, a motor, a clutch between the motor and adding machine, clutch controlling means for throwing said clutch into operation, means for throwing the clutch out of operation after a predetermined operation of the motor, clutch controlling means for throwing said clutch into operation, timing mechanism continuously driven by said motor when in operation, a switch controlling the supply of power to said motor, manipulative means controlling the operation of the clutch and connections controlled by the manipulative means and timing means for maintaining the switch closed until after a predetermined period has elapsed since the last operation of the manipulative means.
15. In a machine of the class described, and in combination with an adding machine proper including a manipulative element, a motor, a timing shaft driven thereby, means including a hammer and an element operated by the stroke thereof for stopping the motor, a disk on the timing shaft normally holding the hammer out of engagement with said element but formed to release the hammer at one point of its revolution and means operated by the manipulative element to prevent the stroke of the hammer.
16. In a machine of the class described, and in combination with an adding machine proper including a manipulative element, a motor, a timing shaft driven thereby, means including a hammer and an element operated by the stroke thereof for stopping the motor, a disk on the timing shaft normally holding the hammer out of engagement with said element but formed to release the hammer at one point of its revolution and means operated by the manipulative element to prevent the stroke of the hammer.
17. In a machine of the class described, and in combination with the adding machine proper, a motor for driving the same, a clutch between the motor and the machine and normally out of engagement, means operated by a manipulative element of the machine for shifting the clutch, a timing shaft driven by the motor and carrying a disk, trip mechanism controlling the supply of power to the motor, means for operating the trip mechanism normally held from engagement therewith by said disk, means controlled by said manipulative element for independently holding the trip operating means from engagement with said tripping mechanism.
18. An adding machine, a motor for driving the same, a motor governor, means for manually setting said governor to start the motor, a trip for operating the governor to stop the motor, means under control of a manipulative part of the machine to restrain said trip from operation and a timing device constantly driven by the motor when in operation adapted and arranged to prevent operation of the trip for a period after the operation of the manipulative part.
19. In an adding machine and in combination with the machine proper, a motor, motor controlling means, timing mechanism constantly driven by the motor during operation of the latter, manipulative means in the adding machine and connections controlled by the timing mechanism for actuating the motor controlling means for stopping the motor after a definite period has elapsed since an operation of the manipulative means.
20. In an adding machine of the class described, and in combination with the adding machine proper thereof, an electric motor, a switch controlling the supply of operating current to the motor, a manipulative element controlling the operation of the adding machine proper by the motor, a timing mechanism progressively advanced by the rotation of the motor, connections controlled by the timing mechanism for opening the switch after the timing mechanism has advanced at least a predetermined extent since the last operation of the manipulative means.
21. In a device of the class described, and in combination with the adding machine proper, an electric motor for controlling the

same, a clutch intermediate the adding machine and the electric motor, and a manipulative means for shifting the clutch, a switch controlling the supply of current to the motor, means for opening said switch after a predetermined interval has elapsed following the last operation of the manipulative means, comprising a member progressively advanced by the rotation of the motor, and a device operated by the manipulative means 10 for preventing the opening of the switch.

JOSEPH RABER.
